GOLF CLUB CLEANING TOOL

Frank Masters Johnson, 9542 S. Yates,
Chicago, Ill. 60617

Filed Apr. 23, 1971, Ser. No. 137,110

Term of patent 14 years

Int. Cl. D21—02

U.S. Cl. D34—5

Fig.1

Fig.2

FIG. 1 is a plan view of a golf club cleaning tool; and
FIG. 2 is a side view of the golf club cleaning tool of
FIG. 1.

The bottom of the tool has the same character and contour as that shown in FIG. 1.

I claim:

The ornamental design for a golf club cleaning tool,
substantially as shown and described.
